UNITED STATES PATENT OFFICE

HAROLD E. WHITE, OF WILKINSBURG, PENNSYLVANIA, ASSIGNOR TO WESTINGHOUSE ELECTRIC & MANUFACTURING COMPANY, A CORPORATION OF PENNSYLVANIA

ACCELERATING SYSTEM

Application filed August 11, 1927. Serial No. 212,941.

My invention relates to the control of electrically operated switches, and particularly to the control of a plurality of such switches or contact members which are intended to be operated in a predetermined sequence.

Control systems of this character are utilized to regulate the current input to motors or other apparatus, in such a manner that a too rapid increase of current is impossible, and means is usually provided for preventing the closure of contact members or switches when the current rises above a predetermined value. The means commonly utilized for obtaining such regulation comprises dash-pots or similar mechanisms for giving an integral of time between the closing of successive contacts. Dash-pots however, require considerable attention to keep them operating efficiently.

The object of my invention, generally stated, is to provide a motor accelerating system which is not only easily manufactured and reliable in operation, but operates without the use of dash-pots or such mechanism.

It is also the object of my invention to provide a new and improved control system for actuating automatically a plurality of contactors in a predetermined sequence.

Another object of my invention is to provide in a motor control system for automatically predetermining the operation of the accelerating means of the motor, independently of the motor itself.

Other objects of my invention will become apparent when the following description is read in conjunction with the accompanying drawings, in which:

Figure 1 is a diagrammatic view of a motor-control system embodying the principal features of my invention, and,

Fig. 2 is a schematic diagram of the system shown in Fig. 1.

Referring now to Figures 1 and 2, of the drawings, a motor 1 having an armature 2 and a series field winding 3 is connected to a source of power supply by means of a double-pole switch 4 through a set of reversing switches 5, 6, 7 and 8, and a starting resistor 9, which in this application is divided into four sections 10, 11, 12 and 13. The shunt-

ing of the sections of resistor is accomplished by means of a plurality of accelerating contactors 14, 15, 16 and 17. In order to control the operation of the reversing contactors and the accelerating contactors, a manually operable switch 19, and an auxiliary motor 20 are provided.

As referred to hereinbefore, the motor 1 may be operated in either direction. When it is desired to operate the motor 1 in what will be termed the forward direction, the reversing contactors 5 and 8 are actuated to establish a circuit from the line conductor 21 through the series field winding 3, conductor 22, the interlock on the reversing contactor 5, conductors 23, 24, the armature 2 of the motor 1, conductor 25, the resistor 9, conductor 26, the interlock on the reversing contactor 8 and conductors 27 and 28 to the opposite line conductor 29. Assuming that it is desired to run the motor in the opposite direction, then the reversing contactors 6 and 7 are closed to establish a circuit from the line conductor 21 through the series field winding 3, conductors 22 and 30, the interlock on the reversing contactor 7, conductor 26, the starting resistor 9, conductor 25, the armature 2 of the motor 1, conductors 24 and 23, the interlock on the reversing contactor 6 and conductor 28 to the opposite line conductor 29.

Circuits for controlling the operation of the reversing contactors 5, 6, 7 and 8 are established through the manually operated controller 19 as shown in detail in Fig. 1. In this system, the reversing contactors 5 and 8 are closed at the same time in order to operate the motor in the forward direction. The manually-operable controller 19 is thrown to the position "a" in the forward direction, to establish an actuating circuit for the contactors 5 and 8 which circuit may be traced from line-conductor 21 through conductor 31, the actuating coils 5a and 8a of the reversing contactors 5 and 8, respectively, connected in parallel relation, conductors 32 and 33, segments 34 and 35 on the controller 19, conductors 36 and 28 to line conductor 29. Therefore, when the controller is thrown to the first position "a" in the forward direction, 100

the contactors 5 and 8, for effecting forward operation of the motor, will be closed.

In order to operate the motor in the reverse direction, the controller 19 is thrown to the right, as viewed in Fig. 1 of the drawing, to the position "a", thereby establishing an energizing circuit for the coils 6a and 7a of the reversing contactors 6 and 7, which extends from the positive line conductor 21 through conductor 31 to the actuating coils 6a and 7a of the reversing contactors 6 and 7, respectively, conductor 37, contact segments 38 and 39 on the controller 19 and conductors 36 and 28 to line conductor 29. When the contactors 6 and 7 are closed, the motor 1 is rotated in the reverse direction.

When starting a large motor, it is common practice to connect a starting resistor such as resistor 9 in series relation with the armature of the motor to prevent excessive starting currents, and the motor is brought up to full speed by decreasing the resistance in the motor circuit by steps, in accordance with the load and size of the motor. It is also common practice to accomplish this by employing magnetic contactors or switches which are regulated to be actuated in successive steps as the nature of the operation requires. In this system, the accelerating contactors or switches 14, 15, 16 and 17 are provided to short-circuit the sections of the resistor.

In order that these accelerating contactors may be utilized to short-circuit sections of the resistor 9, actuating coils 14a, 15a, 16a and 17a, and the holding coils 14b, 15b, 16b and 17b, are provided for operating the accelerating contactors 14, 15, 16 and 17, respectively. The actuating coils 14a to 17a inclusive, may be connected across the source of supply, through the manually-operated controller 19. The manual controller 19, in this illustration, is constructed so that the various actuating coils may be disposed to be energized in any desired order in accordance with the positions, b, c, d and e, or b', c', d' and e', to which the controller may be actuated, but in order that the sequence of operation will not depend upon the actuation of the controller 19 alone, the holding coils 14b, 15b, 16b and 17b are provided on the accelerating switches, or contactors 14, 15, 16 and 17, respectively, and to regulate the current flowing through these coils to provide the proper operation of the accelerating contactors, they are energized in a circuit relation with the armature of a small auxiliary motor 20, which has a shunt field winding 61 connected directly across the line conductors 21 and 29.

The circuit through the holding coils 14b, 15b, 16b and 17b and the armature 62 of the auxiliary motor 20, may be traced from the energized conductor 25 through a portion of resistor 9, moving contact 40, armature 62

of the auxiliary motor 20, conductor 41, the coils 14b, 15b, 16b and 17b, the accelerating contactors or switches 14, 15, 16 and 17, respectively, to conductor 42. It will be observed that circuits, as previously traced, are established from conductors 42 and 25 when either of the pair of reversing contactors 5 and 8, and 6 and 7 are closed.

It is well known that when a motor is first started that a large current will be drawn by the armature of the motor, and this characteristic is taken advantage of in this invention, it being utilized in connection with the auxiliary motor which functions as a valve for regulating the flow of current in the holding coils 14b, 15b, 16b and 17b, for holding the accelerating contactors 14, 15, 16 and 17, respectively, open against the pull of their actuating coils 14a, 15a, 16a and 17a. It will be readily seen that as the auxiliary motor is brought up to speed, its counter electromotive force will increase and the current flowing through the holding coils in series therewith will decrease, permitting the actuating coils to close the accelerating contactors or switches. The holding coils and the actuating coils may be designed to react to various currents, thereby obtaining the proper sequence of operation of the accelerating contactors.

It will be readily understood in view of this, that the operation of the accelerating contactors will be made dependent upon the operation of the auxiliary motor, and also independent of the operation of the main or work motor itself.

Various means may be provided for slowing up the starting of the auxiliary motor such as the fly wheel 44 mounted on the shaft 45 of the auxiliary motor. The fly wheel 44 will require power to overcome its inertia in starting. Therefore, the period over which the starting current will be continued will be somewhat increased, the effect of which will be to increase the length of the time over which the actuating or holding coils 14b, 15b, 16b and 17b will be energized to maintain the accelerating contactors open.

The time required to bring a motor up to full speed is dependent upon the voltage applied to the motor. Therefore, by varying the voltage impressed upon the auxiliary motor, the current flowing through the holding coils may be varied or regulated.

In the invention, as can be observed in this application, I have accomplished the control of circuit flowing in the motor by connecting the auxiliary motor to the source through the resistor 9 by means of an adjustable contact 40 whereby the amount of resistance in the auxiliary motor circuit can be varied to further regulate the effect of the holding coils on the accelerating contactors to meet

various requirements in the operation of the work motor.

Consistent with the theory of the invention, all of the actuating coils 14a, 15a, 16a and 17a may be energized at the same time the work motor is started, without varying the effect of the holding coils which retard and predetermine the period of sequence of the accelerating contactors. In this application, however, it will be noted that the controller 19 is constructed so that the operating coils 14a, 15a, 16a and 17a are energized in sequence as the controller 19 is moved past the points b, c, d and e, in the forward direction, or past the points b', c', d' and e' in the backward direction.

The energizing circuits of the actuating coils, when connected in parallel relation, may be traced from the line conductor 21 through conductor 31, the actuating coils 14a, 15a, 16a and 17a, the conductors 46, 47, 48 and 49 to the contact segments 50, 51, 52 and 53, respectively, on the controller 19 and the contact segment 35 or 39, depending upon the position of controller 19 and through the conductors 36 and 28 to the other line conductor 29.

Therefore, the work motor may be operated with as many sections of the resistor 9 in series with the armature of the work motor as is desired. If the motor is used in connection with hoists or elevators, it is quite frequently desirable to be able to vary the line voltage impressed upon the motor.

When the resistor sections 10, 11, 12 and 13 are shunted, the current will flow through conductors 54, 55, 56 and 57, respectively.

It will be understood that in a system of this nature embodying my invention that by means of the holding coils and the variable method of impressing different voltages upon the auxiliary motor that the periods elapsing between the successive steps in short-circuiting a section of the resistor through the operation of the accelerating switches or contactors can be greatly varied and readily adapted to practically any application where motor acceleration of this character is desired.

While I have described my invention in connection with one particular application, it will be understood that I do not wish to limit myself to the specification or details as there are numerous changes which may be made without departing from the spirit of my invention.

I claim as my invention:

1. In a control system, in combination with an electric work motor, a plurality of accelerating switches for the work motor, means for energizing the actuating coils of the accelerating switches and means comprising a holding coil on each switch connected in series relation with an auxiliary motor for retarding the operation of the accelerating switches in

accordance with the current flowing through the auxiliary motor and means for regulating the initial current flowing through the auxiliary motor.

2. In a control system, in combination with a work motor having a starting resistor, a source of power for the motor, a plurality of electro-magnetic switches for selectively shunting portions of the resistor to accelerate the motor, said switches being provided with restraining coils, a circuit for connecting the restraining coils across the power source, and an auxiliary motor for controlling the operation of the switches, said motor being disposed to control the amount of current flowing in the coil circuit.

3. The combination with an electric motor, a source of power, a starting resistor for the motor, a switch for shunting the resistor, said switch being provided with a closing coil and a lockout coil, means for connecting the coils to the power source, and means connected in series relation to the lockout coil for automatically varying its energization from a maximum to a minimum to thereby effect the release of the switch within a predetermined time interval subsequent to the energization of the motor.

4. In a motor-control system, in combination, a main motor, a starting resistor for the motor, a plurality of switches disposed to shunt different sections of the resistor, said switches being provided with closing and restraining coils, manually operable means for controlling the energization of the closing coils, and an auxiliary motor responsive to the energization of the main motor for controlling the current flowing in the restraining coils, said auxiliary motor being disposed to permit a relatively large initial current to flow through all of said restraining coils, and gradually reduce the said coil current to effect the closure of the shunting switches in a predetermined operating sequence.

5. In a motor-control system, in combination, a source of power, a work motor disposed to be connected to the source of power, a starting resistor for the motor, a switch provided with a closing coil for shunting the starting resistor, a circuit for actuating the switch connected across the source of power for energizing the closing coil, means energized from the power source for opposing the operation of the switch, and an auxiliary motor cooperative with the opposing means for controlling the operation of the switch.

6. In a control system, in combination, a source of power, a work motor disposed to be connected across the power source, a starting resistor for the work motor, a switch provided with a closing coil for shunting the resistor to accelerate the work motor, a circuit for energizing the closing coil to actuate the switch, current-responsive means for

biasing the switch to the open position, an auxiliary motor for controlling the current flowing in the current-responsive biasing means in accordance with variations of its 5 counter-electromotive force, thereby to govern the closing operation of the shunting switch independently of the load on the work motor.

7. In a control system, in combination, a 10 work motor, a starting resistor for the motor, a source of power, means operable to connect the motor and starting resistor across the source of power, bridging switches for the resistor, said switches being provided with differentially-acting operating coils, a master 15 switch operable to control the energization of certain of the operating coils to effect resistor-bridging operations, an auxiliary motor connected in shunt-circuit relation 20 with a portion of the resistor and in series-circuit relation to the other operating coils of the bridging switches for varying the energizing current of said coils to govern the closing operation of said switches, and 25 energy-absorbing means disposed to retard the acceleration of the auxiliary motor.

8. In a control system, in combination, a work motor, a starting resistor for the motor, a source of power for the motor, means operable to connect the motor and starting resistor across the source of power, a plurality 30 of bridging switches for the resistor, said switches being provided with differentially-related actuating coils, means for individually energizing certain of the actuating coils to effect a closing operation of the bridging switches, and an auxiliary motor variably connected across the starting resistor having an armature in series-circuit 35 relation with the coils oppositely related to the individually energized coils to restrain the closing operation of the bridging switches in accordance with the variations of the auxiliary motor current.

40 45 In testimony whereof, I have hereunto subscribed my name this 3rd day of August, 1927.

HAROLD E. WHITE.
